UNITED STATES PATENT OFFICE.

ABEL T. ATHERTON, OF LOWELL, MASSACHUSETTS.

ELEVATOR FOR CASH AND PARCEL CARRIERS.

SPECIFICATION forming part of Letters Patent No. 298,654, dated May 13, 1884.

Application filed July 23, 1883. (No model.)

To all whom it may concern:

Be it known that I, ABEL T. ATHERTON, of Lowell, in the State of Massachusetts, have invented certain new and useful Improvements in Elevators for Cash and Parcel Carriers, of which the following is a specification.

My invention has reference to the device, termed "elevator," employed to raise and deliver onto the track the cash or parcel carrier, and is applicable more particularly to the elevator used at the central or distributing station.

Heretofore, so far as I am aware, cash or parcel carrier elevators have been lifted or raised by hand. It is my object to furnish a convenient arrangement by which the elevator can be operated by power—such as air, steam, or water. To this end I combine with the elevator a piston, by whose movements the elevator is actuated, and a cylinder, into which the motor-fluid is admitted for the purpose of moving the piston in the direction requisite to raise the elevator, the admission of the motor-fluid being controlled by a valve or cock to be operated by hand. In order to make provision for the descent of the elevator, I combine with it means whereby when it reaches the upper terminus of its course an exhaust is automatically opened to permit the escape of the confined air, water, or other motor-fluid from beneath the piston, thus permitting the latter, with the elevator, to descend by gravity; and I further combine with the foregoing instrumentalities means whereby when the elevator reaches the lower terminus of its course the exhaust is automatically closed.

The nature of my invention and the manner in which the same is or may be carried into effect will be readily understood by reference to the accompanying drawings, in which—

Figure 1 is a side elevation of an apparatus embodying the invention. Fig. 2 is a longitudinal vertical section of the same.

The elevator A may have any suitable form of cradle on its top to contain the cash-carrier and to deliver it onto the track B, which is located at the point to which the elevator rises. The elevator is mounted on a rod or stem, C, which at its lower end is attached to a piston, D, which moves in a vertical cylinder, E, of proper length, and is of course

packed to prevent the fluid from passing between it and the walls of the cylinder. The motor-fluid, whether gas, air, water, or steam, obtained from any suitable or convenient source of supply, enters the lower part of the cylinder through a conduit, F, controlled by a slide valve or gate, a, or any other suitable cock or valve arrangement. The valve a in this instance is operated by a manual key or lever, b, pivoted at b', and having a spring, c, under its outer or free end, so that as soon as the finger or hand is removed from this end of the key or lever the spring will at once move the latter in the direction requisite to cut off further supply of the motor-fluid to the cylinder. Spring-controlled valves or cocks of other known forms can be used in lieu of the one just described. What is desirable is a spring-controlled admission or supply valve, which, when released from the hand, will automatically cut off the entrance of the motor-fluid.

Under the arrangement thus far described it will be seen that if, when the elevator is in its lowest position, the admission-valve be opened, as indicated by dotted lines in Fig. 1, the fluid entering the cylinder beneath the piston will at once force the latter, together with the elevator, upward to the position shown by dotted lines in Fig. 1, bringing the elevator in line with the track and causing the carrier (shown at x in dotted lines) to be delivered therefrom onto the track. It requires only a momentary depression of the key b to effect this result. The finger is then taken off and the spring c at once closes the valve.

To allow the elevator to descend to its original position, means of course must be provided to permit escape of the motor-fluid confined in the cylinder below the piston. To this end any suitable escape valve or cock can be employed, whether operated by hand or otherwise; and if operated by hand it may be spring-controlled and otherwise arranged like the admission-valve, so that by pressing the key of the exhaust-valve the latter will be opened and can be kept so until the elevator has completed its descent. I prefer, however, to provide for the automatic operation of the escape or exhaust valve so that it will automatically open at the time the elevator has com-

pleted or nearly completed its ascent, and will thus permit the latter to descend immediately after having delivered its carrier onto the track; and I also so arrange and combine the 5 valve-operating mechanism that the said valve will at about the time the elevator has completed its descent be again automatically closed. A convenient arrangement for this purpose is shown in the drawings in illustration 10 of my invention.

The exhaust or escape valve G is hung on the exterior of the cylinder at d, so as to fit tightly over and close the escape-opening e in said cylinder. A rod, f, which I term the 15 "shifting-rod," is arranged and held in guides in a bracket, g, in which it can move up and down. This rod moves in contact with and bears against the outer face of the valve G, so that when in its lowermost position it presses 20 and holds the valve closely over the opening e. The upper end of the rod is provided with a headed pin, h, which works up and down in a vertical slot, g', in a stationary piece, i, and serves at once as a guide for the rod, and also 25 as a dog by which the rod can be shifted. The elevator, or stem connected therewith, is provided with two shoulders, j k, so placed with reference to the dog that when the elevator has about completed its ascent the lower shoul- 30 der, j, will meet and lift the dog, thus raising the shifting-rod and releasing the exhaust or escape valve, which will at once open and permit the motor-fluid to blow off or escape from the cylinder. The upper shoulder, k, on the 35 contrary, when the elevator has about completed its descent, meets and depresses the dog, and thus pushes down the shifting-rod, with the effect of tightly closing and locking the exhaust-valve. The meeting faces of the 40 valve and rod have a cam or equivalent formation, so that while the valve is entirely free when the rod is up it will, when the rod de- scends, be forced up into place over the es- cape-opening. Thus when the elevator has 45 ascended the exhaust-valve is automatically

opened, and remains open until the elevator has descended, at which time the valve is automatically closed and locked in place.

Any suitable provision for carrying off and disposing of the exhaust fluid can be made, 50 this depending, to some extent, upon the kind of motor-fluid used.

I do not restrict myself to the specific means hereinbefore described for obtaining the automatic action of the exhaust-valve. Various 55 other means for the purpose will readily suggest themselves to the skilled mechanic.

What I claim herein as new and of my own invention is—

1. The combination, with the carrier-elevator, the elevator-actuating piston, and its containing-cylinder, of an exhaust or escape valve arranged and operating to automatically open 60 at or near the time the elevator completes its upward movement, substantially as and for 65 the purposes hereinbefore set forth.

2. The combination, with the carrier-elevator, the elevator-actuating piston, and its containing-cylinder, of an exhaust or escape valve, and valve-operating mechanism actuated by 70 the elevator, or some part moving in unison therewith, to open and close said exhaust-valve at the times and in the manner substantially as hereinbefore set forth.

3. The combination of the carrier-elevator, 75 the elevator-actuating piston, its containing-cylinder, the spring-controlled admission-valve, the exhaust-valve, and exhaust-valve-operating mechanism, actuated by the ele- 80 vator, or some part moving in unison therewith, at or near its extremes of movement to open and close said exhaust-valve, the combination being and acting substantially as hereinbefore set forth.

In testimony whereof I have hereunto set 85 my hand this 14th day of July, 1883.

ABEL T. ATHERTON.
